RAIL HEAD CLAMP

Stanley H. Clark, Provo, Utah, assignor to United States Steel Corporation, a corporation of New Jersey

Application June 26, 1952, Serial No. 295,727

6 Claims. (Cl. 246—477)

The present invention relates to clamping devices and has for its general object the providing of an improved clamp which is particularly suited for detachably mounting signals and the like on railroad rail heads of various sizes.

The nature of the invention and its distinguishing features and advantages will be fully apparent from the following detailed disclosure and the appended claims when read in connection with the accompanying drawings in which:

Figure 1 is an elevational view showing the clamp of my invention in clamping engagement with a rail head;

Figure 2 is a view similar to Figure 1 showing the clamp in open non-clamping position; and

Figure 3 is a plan view of Figure 2.

Referring more particularly to the drawings, reference numeral 2 indicates a relatively stationary clamp arm having an angularly bent portion 4 at its lower end and a warning signal 6 affixed to its upper end by means of bolts or rivets 8. The bent end portion 4 of the clamp arm 2 has a channel shaped jaw 10 laterally disposed thereon adjacent its end. The jaw 10 is shaped to engage a rail head W, as shown in Figure 1, and has an opening suitably shaped for this purpose which faces toward a projection of the longitudinal axis of the straight portion of the clamp arm 2. A movable clamp arm 12 which is somewhat shorter than the stationary clamp arm 2 is pivotally mounted intermediate its ends onto the clamp 2, as at 14, adjacent the junction of the straight and bent portions of the stationary clamp arm. The lower end of the movable clamp arm 12 is provided with a rail head-engaging jaw 16 which matches the jaw 10 and is positioned adjacent thereto with its opening facing the opening of jaw 10. A rounded projection 18 having a hole 20 therethrough is provided on the end of the movable clamp arm 12 adjacent to the jaw 16.

An actuating arm 22 which is substantially L-shaped in form is pivotally attached by its one end 24 to the clamp arm 2 intermediate the pivotal mounting 14 of the clamp arm 12 and the signal-bearing end of the clamp arm 2. A helical tension spring 26, having closely spaced convolutions, extends between and is connected at one end to an anchor post 28 projecting from the surface of the clamp arm 12 adjacent its upper end. The spring 26 is connected by its other end to an anchor post 30 projecting from the surface of the actuating arm 22 adjacent its end 24. The opposite end 32 of the actuating arm 22 is bifurcated and is provided with a hole 34 extending transversely through the bifurcations. A transverse wall 36 is provided between the bifurcations adjacent the bases thereof.

A projecting handle member 38 is affixed to the actuating arm to facilitate its manipulation, and a stop member 40 is provided on the surface of the actuating arm opposite the handle 38 to restrict the rotation of the arm past the clamp arm 2.

In operation, the jaw 10 is affixed to the rail head W, and the end 32 of the actuating arm 22 is moved down-

2

wardly to the position shown in Figure 1 to cause clamp arm 12 to move relative to the clamp arm 2 to achieve engagement of the rail head W by jaw 16 opposite jaw 10. Movement of the actuating arm in this direction causes stretching of the spring 26 which in turn pulls the upper end of the movable clamp arm 12 to move the jaw 16 into positive engagement with the rail head. When the jaws 16 and 10 engage the rail head, the bifurcated end 32 of the actuating arm engages the rounded projection 18 of the movable clamp arm, and the transverse wall 36 abuts the outer surface of the rounded projection 18 to prevent further movement of the actuating arm toward the jaw 16. In this position, the holes 20 and 34 are in alignment so that a lock may be inserted therethrough to secure the clamp and prevent its removal by unauthorized personnel.

In order to provide positive locking action on the part of the actuating arm when its end is moved toward the jaw 16, the spring 26 must be so positioned that its axis is below the axis of the pivotal mounting of the actuating arm when the jaws 16 and 10 are in engagement with the rail head. This arrangement eliminates the need of any other holding means to maintain the actuating arm in position when the jaws are in clamping engagement with the rail head. Positioning the spring in this manner creates a continuing force urging the upper end of the movable clamp 12 toward the pivotal connection of the actuating arm 22. At the same time, the actuating arm is prevented from moving further towards the jaws by means of its abutting engagement with the rounded projection 18 as described above and shown in Figure 1. Thus, all the forces are directed to holding the jaws in tight engagement with the rail head when the actuating arm is pulled downwardly in operating position.

When it is desired to remove the clamp from the rail head, the handle 38 is grasped and the actuating arm 22 is moved upwardly to the position shown in Figure 2. This movement reduces the tension of the spring and moves the axis of the spring 26 above the pivotal connection of the actuating arm. As the arm 22 is rotated toward the limit of its upward movement, the upper end of the movable clamp 12 is caused to move downwardly to the position shown in Figure 2. This movement obviously causes the jaw 16 to move away from the rail head W thus freeing the clamp from engaging position.

It will be noted that the device of my invention may be clamped on various sized railroad rails without adjustment by virtue of the spring tension arrangement incorporated therein. This feature permits universal use of the device on railroad tracks as well as specially sized equipment tracks such as mine tracks, etc. In addition, the spring tension feature assures positive clamping action at all times. In the event of vibration or oscillation of the signal in strong wind, the disturbance merely causes the clamp to grip more and more securely.

It is not intended to limit the scope of this invention to the use thereof for holding warning signals on railroad tracks, but rather to include any uses to which the invention lends itself and to any modification of the invention within the scope of the claims hereinafter stated.

I claim:

1. A clamping device for detachably mounting an object on a rail head and the like which comprises a relatively long clamp arm, a rail head-engaging jaw adjacent one end of said arm, means for supporting said object at the other end of said arm, a short clamp arm pivotally mounted intermediate its ends on said long clamp arm, a rail head-engaging jaw on one end of said short clamp arm adjacent the jaw on said long clamp arm, an actuating arm pivotally mounted by one end to said long clamp arm at a point intermediate the pivotal mounting of said short clamp arm and the object supporting end

of said long clamp arm, and a helical spring having closely spaced convolutions extending between and connected to said actuating arm and said short clamp arm and adapted to move said short clamp arm relative to said long clamp arm when said actuating arm is moved, means for restricting the movement of said actuating arm toward said jaws.

2. A clamping device as defined in claim 1 characterized by the axis of said spring being between the axis of the pivotal mounting of said actuating arm and the axis of the pivotal mounting of said short clamp arm when the jaws are in engagement with said rail head.

3. A clamping device for detachably mounting an object on a rail head and the like which comprises a relatively stationary clamp arm, an angularly bent portion at one end of said arm, means for supporting said object at the opposite end of said arm, a channel shaped rail head-engaging jaw laterally disposed in said bent end portion normal thereto with the opening of said jaw facing toward a projection of the longitudinal axis of the straight portion of said arm, a movable clamp jaw pivotally mounted intermediate its ends on said stationary clamp arm at a point adjacent said bent end portion, a channel shaped rail head-engaging jaw laterally disposed adjacent one end of said movable clamp arm and normal thereto adjacent the jaw on said stationary clamp arm with the opening of said jaws facing each other, a rounded projection having a hole therethrough on the end of said movable clamp arm adjacent the jaw thereon, an actuating arm pivotally mounted by one end to said stationary clamp arm at a point intermediate the pivotal mounting of said movable clamp arm and the object supporting end of said stationary clamp arm, the end of said actuating arm opposite its pivotal mounting being bifurcated

and having a transverse hole therethrough, a transverse wall between said bifurcations adjacent the bases thereof, and a helical spring having closely spaced convolutions extending between and connected to said actuating arm and said movable clamp arm and adapted to move said short clamp relative to said stationary clamp arm when said actuating arm is moved, said bifurcated end of said actuating arm being engaged with the rounded projection of said movable clamp arm with said transverse wall abutting said projection and the hole through said bifurcated end being in alignment with the hole through said rounded projection when said jaws are in engagement with said rail head.

4. A clamping device as defined in claim 3 characterized by the axis of said spring being between the axis of the pivotal mounting of said actuating arm and the axis of the pivotal mounting of said movable clamp arm when the jaws are in engagement with said rail head.

5. A clamping device as defined in claim 4 including a stop member attached to and projecting from the surface of said actuating arm and adapted to engage the edge of said stationary clamp arm to limit the movement of said actuating arm when said jaws are moved away from each other.

6. A clamping device as defined in claim 5 characterized by an elongated handle member being attached to and projecting normal to the surface of said actuating arm for manipulating the same.
